UNITED STATES PATENT OFFICE.

AUGUSTUS E. SNYDER, OF BLOOMFIELD, NEW JERSEY, ASSIGNOR TO WESTINGHOUSE LAMP COMPANY, A CORPORATION OF PENNSYLVANIA.

CARTON.

Application filed June 6, 1918. Serial No. 238,557.

To all whom it may concern:

Be it known that I, AUGUSTUS E. SNYDER, a citizen of the United States, and a resident of Bloomfield, in the county of Essex and State of New Jersey, have invented a new and useful Improvement in Cartons, of which the following is a specification.

My invention relates to cartons for incandescent lamps and particularly that type of 10 carton designed to accommodate an individual lamp.

It has for one of its objects, the provision of a carton that shall be adapted to receive and resiliently support an incandescent lamp 15 or other fragile articles in such a manner that it may withstand shipment and handling without damage or breakage.

Another object is the provision of a carton of a collapsible or knocked-down type 20 which may be easily and quickly assembled so as to constitute an enclosure and support a lamp so as to prevent breakage of its glass parts or the disarrangement of its filament.

By reason of the extremely fragile character of the filament of incandescent lamps 25 it is necessary to exercise great care in packing lamps for shipment in order to insure their arrival at their destinations without having suffered damage or breakage. The 30 packing devices that have heretofore been supplied have been expensive, and have not been successful to a satisfactory degree in preventing breakage of the filaments or other parts. It is a function of the present invention to provide an individual carton that 35 shall be simple and economical to manufacture and assemble, and in which the lamp may be safely handled and shipped.

In the accompanying drawings Fig. 1 is 40 a longitudinal sectional view of a carton embodying my invention; Fig. 2 is a plan view of one form of the carton unfolded; Fig. 3 is a similar view of a modified form; Fig. 4 is a perspective view of the modification 45 shown in Fig. 3; Fig. 5 is still another modification of the forms shown in Figs. 2 and 3; and Fig. 6 is a view showing the carton, in a partly assembled condition, formed from the style body shown in Fig. 5.

Referring to the drawings, particularly 50 Figs. 1 and 2, the carton is formed from a single piece of cardboard, blanked out to provide a body portion creased longitudinally to form side faces or panels, 1, 2, 3, 4, 55 5 when the cardboard is folded. Extending

laterally from the ends of one of the sides, such as 3, are end members 6 and 7 which are equal in width to the side 3 and formed integrally therewith. The end members 6 and 7 are creased to make easily foldable 60 end closures for the respective ends of the carton. These creases are formed in such a manner that portions 8 and 9 of each of the ends function, firstly; as a spacing means for regulating the depth from the ends of 65 the carton at which the transverse portions 10 and 11 are positioned inwardly or spaced relatively to each other, and secondly; as a support for said transverse portions. The transverse portion 10 has a plurality of slits 70 radiating from a common central point, which are designed to afford a yielding contacting surface with the contained article, which, if an incandescent lamp, would be the tip portion of the bulb. The transverse portion 11 has an aperture large 75 enough to permit the protruding of a portion of the article, but is smaller than its body, and in the case of a lamp, is adapted to engage the base at the point where it 80 joins the bulb. By this construction, an incandescent lamp may be resiliently suspended between the transverse end members 10 and 11, and be held out of contact with the adjacent sides of the carton. To pro- 85 vide a fastening means to hold the end closures in position, portions 12 and 13 are provided which are adapted to be turned outwardly and fold back upon the adjacent side face as more fully described hereinafter. 90

In assembling the carton from the blank shown in Fig. 2, the body portion is first bent along the sectional creases, thus forming a rectangular case or shell having an over-lapping side 5. Either of the end 95 members may then be folded inwardly, preferably end 7, and portion 13 turned outwardly against the adjacent face 1. The base of the lamp is passed thru the aperture in the transverse section 11 and the 100 end 6 is then folded in a similar manner with the tip projecting from the radial slits, and portion 12 bent downwardly exteriorly of the case. The over-lapping side 5 is now folded over so as to engage the bent 105 over portions 12 and 13, thus firmly securing the end closures in position. To maintain the face 5 in place, a label or similar means is pasted over the free edge thereof, along the adjacent corner or edge of the 110

2
carton, thus affording a simple means for completely fastening or closing the carton.

In the modification shown in Figs. 3 and 4, the side faces 1 and 5 are provided at 4, their upper and lower edges with rectangular-shaped slots 14. The positioning of these slots from the adjacent edges is determined by the length of the article to be placed in the carton. The end members 6 10 and 7 have their depth-regulating portions 8 equal to the distance of the slots 14 from the respective end edges of the faces 1 and 5, and there is formed adjacent each of the transverse portions 10 and 11, a tongue 15 15 provided with teeth or catches adapted to be received by or passed thru the slots 14 and engage the adjacent exterior surface of the carton when assembled as shown in Fig. 4. This form of closing or sealing means, in 20 addition to saving stock, dispenses with the necessity of any auxiliary fastening devices.

By referring to Figs. 5 and 6 it will be seen that the modification illustrated there- 25 by, consists of a carton of 4 side faces with one of the outer side faces terminating in a short foldable edge portion, which may be glued or otherwise suitably secured to the under surface of the opposite side face edge. 30 This construction permits of a preliminary or partial assembling of the carton in ad- vance of its use and renders it collapsible so that it may occupy a minimum of space. In this modification, the end members 6 and 35 7 have their respective spacing portions 8 and 9 of equal width and, when folded into position, the portions 9 come flush with the edges at the ends of the carton and may be held in place by stapling or in any other ap- 40 proved manner.

From the above description it will be apparent that my invention contemplates the provision of a carton characterized by sim- 45 plicity of construction and which will resi- dently support a fragile article so that the same is entirely enclosed in the sense that no portion of it is exposed, and thus secured or immuned from damage occasioned by ordinary or reasonable handling.

50 While this invention has been set forth in certain preferred embodiments, it will be understood that modifications might be made without departure from the spirit and scope thereof.

55 What is claimed is:

1. An incandescent lamp carton comprising a strip of material folded into five panels, the outer panels being overlapped, so as to form four side walls of the carton, the 60 middle panel being provided with extensions folded inwardly to form end closures for the carton, said end closures being re- 65 spectively provided with an aperture to accommodate the base of the lamp and a tip supporting means and each being provided

with a flap engaging the overlapping panels, to hold the container in assembled form and secure each end closure in position and spaced from the adjacent edges of the side walls. 70

2. An incandescent lamp carton comprising a blank of material folded into five sec- 75 tions, the outer sections being overlapped to form four side walls of the carton, enclos- ing a space of greater dimensions than that of the lamp to be contained therein, the middle section being provided with extensions folded inwardly to form end closures for the carton, one of said closures being adapted to support the base of the lamp and the other 80 provided with tip supporting means, the space between said end closures and the location thereof being such that the lamp may be suspended therebetween out of engage- 85 ment with the side walls of the carton, with clearance for the base and tip of the lamp with respect to the ends of the carton and each end closure being provided with a tongue inserted in a slit in the overlapping 90 sections to hold the carton assembled and also secure the end closures in the proper 95 positions.

3. An incandescent lamp container com- 100 prising an integral strip of cardboard or the like, folded into five panels, the outer panels being overlapped so as to form the four side walls thereof, the middle panel be- 105 ing provided with portions extending in opposite directions and folded inwardly to form end closures for the container and to support a lamp therein, one of said end clo- 110 sures being provided with an aperture suit- able to accommodate the base of the lamp and the other of said end closures being pro- 115 vided with tip supporting means comprising 120 radially disposed slits, the space between said end closures being such that the lamp is suspended therebetween and the depth of said end closures being such that clearance 110 is provided for the tip and base of the lamp from the top and bottom edges of the side walls, each of said end closures being pro- 115 vided with a flap engaging the overlapping 125 panels to perform the double function of holding said panels together for the pur- 130 pose of maintaining the container in as- sembled formation and to hold the end clo- 135 sures in position, spaced from the adjacent edges of the side walls.

4. An incandescent lamp container com- 140 prising an integral piece of cardboard or the like, folded into five panels, the outer panels thereof being overlapped to form four side walls for the container, enclosing 145 a space of greater dimensions than that of the lamp to be enclosed therein, the middle panel provided with extensions folded to 150 form end closures for the container, one of said closures being adapted to support the base of the lamp and the other provided 155

with tip supporting means comprising radially disposed slits, the space between said end closures and the location thereof being such that the lamp may be suspended therebetween out of engagement with the side walls of the container and with the tip and base thereof spaced respectively from the upper and lower edges of the side walls of the container and each end closure provided

10 with a tongue inserted in slots in the over-

lapping side panels to serve the double function of holding the container assembled and secure the end closures spaced in proper relation to the side walls of the container.

15 In testimony whereof, I have hereunto subscribed my name this 29th day of May, 1918.

AUGUSTUS E. SNYDER.
